CONTAINER

Martin Brandon, Villa Park, Ill.

Application March 3, 1930. Serial No. 432,709

10 Claims. (Cl. 229—4.5)

This invention relates to improvements in containers and it consists of the matters herein-after described and more particularly pointed out in the appended claims.

5 Containers are ordinarily made from either wood, metal or paper according to the commodity for which it is to be used in its intended purpose. For the lighter commodities such as certain foodstuffs, containers of paper or fibre may be used to advantage.

10 However, certain commodities require stronger containers and in this instance boxes, kegs and barrels made of wood are employed and sometimes such containers are made entirely of metal.

15 While each of said kinds of containers may have its advantage when used for a particular commodity it has innumerable disadvantages. For instance, containers for heavier commodities must, of course, have greater strength. Ordinarily heavier stock or material is employed so that the cost of manufacture as well as cost of shipment is increased in proportion.

20 The primary object of the invention is to provide a container especially adapted for the heavier commodities, which container is so constructed as to have all of the advantages of the materials now employed therefor without the usual disadvantages which are inherent therein.

25 Another object of the invention is to provide a container which though light in weight, is strong and durable, which may be shipped to the user in knock-down form for easy assembly as required, thus reducing shipment costs and which may be produced at prices competitive with those of containers as now used.

30 Still a further object of the invention is to provide a container of this kind having a composite side wall structure made up of a metallic sheet covered on both sides with non-metallic sheets, portions of the metallic sheet being flanged over upon one of the non-metallic sheets to not only protect the marginal parts thereof but also to stiffen the entire structure.

35 Still a further object of the invention is to provide a simple and efficient method of making the containers which may be readily carried out by unskilled help.

40 These objects of the invention together with others as well as the many advantages thereof, will more fully appear as I proceed with my specification.

In the drawings:—

45 Fig. 1 is a view in front elevation of a composite blank from which the body of my improved container is made before the same has been treated

to certain folding operations on the marginal portions thereof, as will later appear.

Fig. 2 is a view in end elevation on an enlarged scale of the blank shown in Fig. 1.

Fig. 3 is a view in side elevation of the blank shown in Fig. 1 after certain flanging operations has been carried out on the margins thereof.

Fig. 4 is a longitudinal sectional view on an enlarged scale through the blank of Fig. 3 as taken on the line 4—4 thereof.

Fig. 5 is a transverse sectional view on an enlarged scale through the blank of Fig. 3 as taken on the line 5—5 thereof.

Fig. 6 is a perspective view showing how the blank of Fig. 3 is formed to provide the body of the container.

Fig. 7 is a perspective view of a fragment of hook strip employed in my improved container to hold the blank of Fig. 3 in body form as shown in Fig. 6.

Fig. 8 is a perspective view of one form of finished container embodying my invention.

Fig. 9 is a transverse vertical section on an enlarged scale, through one end of the finished container.

Fig. 10 is a transverse vertical sectional view on an enlarged scale through the seam of the body as taken on the line 10—10 of Fig. 8.

Fig. 11 is a view in side elevation of a modified form of blank from which another container body embodying my invention may be formed.

Fig. 12 is a transverse vertical sectional view through the same on an enlarged scale as taken on the line 12—12 of Fig. 11.

Fig. 13 is a view similar to Fig. 12 after parts of the top and bottom margins of the blank shown in Figs. 11 and 12, have been turned over to form a partly finished flange thereon.

Fig. 14 is a view similar to Fig. 13 after said margins have been again turned over to form the finished flange therefor.

Fig. 15 is a vertical sectional view also on an enlarged scale, through an end portion of a container embodying a modified form of the invention.

Referring now in detail to that embodiment of the invention illustrated in Figs. 1 to 10 inclusive of the accompanying drawings:—1 indicates as a whole a blank from which the body of one form of my improved container is made. Said blank comprises a core of sheet metal 2 of the desired area or shape and to each side of the same is fixed in any suitable manner, inner and outer non-metallic sheets or coverings 3

and 4 respectively. Said non-metallic sheets or coverings are each of an area smaller than that of the metallic sheet to leave top and bottom margins 5—5 and end margins 6—6. These 5 sheets, of course, will have a length and width corresponding to the height and circumference of the container to be made. For the core, I may use metallic sheets which have imperfections therein or are more or less rusty or are in such 10 other condition that they cannot be sold as first class sheets.

For the inner and outer non-metallic sheets or coverings I find that jute stock paper will well serve the purpose and preferably the same 15 are secured to the core by an adhesive of any suitable kind. In this instance, I have referred to said non-metallic sheets as "inner" and "outer" but this is only for convenience and is used to designate the positions these sheets occupy in 20 the finished container; that is, upon the inside and the outside thereof. Again I have stated that said inner and outer sheets are of paper but this is to be considered as by way of example only because as it is apparent other materials may be 25 used having characteristics which makes them adaptable for the purpose.

With a blank such as shown in Figs. 1 and 2, I turn the top and bottom margins 5—5 of the 30 core 2 or metallic sheet over upon the outer non-metallic sheet 4, along lines disposed in the planes of the top and bottom edges of the sheets 3 and 4 to form a flange 5' (see Fig. 5) along the top and bottom of the blank. These flanges overhang and tightly engage the similar margins of 35 the outer non-metallic sheet 4 and thus protect said margins against tearing in use.

I then turn the end margins 6—6 of the core or 40 non-metallic sheet over upon but not tightly down upon the outer non-metallic sheet 4, along lines as defined by the edges of said last mentioned sheet to there provide hook flanges 7—7 as best shown in Fig. 4. The blank thus far described, though made of but a thin sheet metal core with inner and outer paper coverings, is 45 materially reinforced in strength and is somewhat stiffened by the flange constructions described.

The blank is now ready for forming into body 50 shape. Such a blank is rolled in a direction parallel the flanges 5'—5' to impart a somewhat curved or circular shape, with the non-metallic sheet 3 on the inside thereof. With the blank thus rolled, the two ends bearing the hook flanges 7—7 may be readily brought into engagement 55 with each other. While holding said ends together temporarily, in the condition shown in Fig. 7, I apply a locking strip 8 thereto. Such a strip which comprises an outer wall 9 and inwardly facing inner flanges 10—10 is slipped 60 upon the now adjacent hook fingers 7—7 from one end as best shown in Fig. 6.

When the locking strip is in place, the flanges 65 10—10 will be engaged under the hook flanges 7—7 and pressure is then imposed upon said strip 70 which flattens down the flanges thereof so that the two ends of the blank are securely locked or held against separation. Thus there is provided a tubular body such as is shown in Fig. 6, which is circular in cross sectional shape. It is apparent that should other cross sectional shapes be desired, such as rectangular, hexagonal, octagonal and the like, the blank shown in Fig. 3 could readily be creased to provide such shapes without departing from the spirit of the invention. The circular shape of body described is 75

therefore to be considered merely as illustrative of but one form in which it is possible to produce in my improved container.

With a tubular body as thus far described, are associated closures 11—11, one for each end which closures are preferably but not necessarily of the same construction I find it convenient to make such a closure in the form of a wooden plug like body, having an inner portion 12 of an axial length greater than that of the body flanges 80 5'—5', and of a diameter approximating the inside diameter of the body, and an outer portion 13 of a shorter axial length but of a diameter approximating the outside diameter of the body. With such a closure it is apparent that an annular shoulder 14 is provided between said portions 12 and 13. On the outer surface of the closure I provide a sheet of paper 15 that not only acts to finish off the closure but also protects the closure against moisture which might 85 split and damage the same.

I apply one closure to one end of the body by inserting the portion 12 into said head until the shoulder 14 engages upon the extremity of said body as best shown in Fig. 9. I then drive suitable nails or brads 16 through the body into part 100 12 of the closure. Preferably these nails or brads are positioned as close to the edge of the associated flange 5' as is convenient. Thus one closure is provided for one end of the body of 105 the container. The container is now ready for filling with the desired commodity from the other end which, of course, is still open after which said end is closed by another closure 11 such as just above described.

A container as above described is indeed strong and rigid and will amply withstand the rough treatment it receives in use when loaded with a fairly heavy commodity. One of the uses for which the container above described is especially 115 adapted is for the shipment of welding rods and the container amply withstands the great strain thereof without opening up or denting. In this respect it is also pointed out that it does not "sweat" so that the rods remain in their original 120 new condition without rusting until the container is opened. No matter how long such containers remain in storage, their contents remain unchanged. Because of the inner non-metallic sheet 3, the commodity cannot come into direct 125 contact with the metal sheet or core.

My improved container is flexible so far as manufacturing problems are concerned and for the much heavier commodities where heavier containers are desired the same may be produced in a number of different ways. For instance, the core may be made of heavier metallic sheet stock and the same non-metallic sheets before mentioned may be used in connection therewith or the same metallic sheet as first 130 described may be used for the core and a heavier 135 paper sheet may be used for the inner and outer coverings, or said coverings may be made up of one or more plies. In Figs. 11, 12, 13 and 14 this last mentioned arrangement is shown and 140 will now be described.

In Figs. 11 and 12 the metallic sheet or core 14 is shown as provided with inner and outer non-metallic sheets or coverings 3^a and 4^a respectively, each comprising a plurality of superposed, adhered together plies leaving the margins 5^a and 6^a as before. A portion of each margin 5^a—5^a is bent over upon itself to form a double thickness flange 5^b as shown in Fig. 13 145 after which said double thickness flange is 150

turned outwardly and over upon the associated margins of the plys constituting the outer covering 4^a. Thus a much stronger as well as a somewhat heavier container may be made.

5 In Fig. 15 is illustrated a further modified form wherein 1^b indicates the metallic sheet or core and 3^b and 4^b indicate the inner and outer non-metallic sheets or coverings therefor. In this instance, the marginal part of the metallic sheet is of such width as to be folded over to provide a double thickness flange 17 overhanging the top margin of the inner non-metallic sheet 3^b and a single thickness flange 17^a overhanging the top margin of the outer non-metallic sheet 15 4^b. Thus a portion of the non-metallic sheet is employed to overhang the top margins of both non-metallic sheets so that a strong stiff construction is provided for the container end so that it cannot be easily misshaped.

20 From the above it is apparent that the improved container is flexible so far as its manufacture is concerned as it is open to a number of variations. Thus the container may be made to meet the requirements of any commodity to be shipped therein.

Again the component parts of the container may be shipped direct to the user with the blanks either in the flat condition or rolled to the desired approximate curvature for easy assembly. 30 Thus shipping rates and space as well as storage space is materially reduced with a resulting saving and the containers may thereafter be readily assembled as the occasion demands. The improved container has the advantages of all paper, wood or metal containers without the disadvantages thereof and can be manufactured at competitive prices with any or all of them.

While in describing the invention I have referred in detail to the form, arrangement and construction of the several parts thereof as well as to the manner in which it may be made, the same is to be considered merely as illustrative so that I do not wish to be limited thereto except as may be pointed out in the appended claims.

45 I claim as my invention:—

1. The method of making a container body which consists in providing a metallic sheet having top and bottom edges and end edges, applying a non-metallic sheet to one side of said metallic sheet so as to leave a marginal part of the metallic sheet exposed along said top and bottom and end edges, flanging said top and bottom marginal parts of the metallic sheet over upon portions of the non-metallic sheet, forming the end margins of the metallic sheet with hook flanges to provide a partially finished blank, shaping said blank into tubular form to bring the hook flanges thereof together in operative relation and then securing them together in said relation.

2. The method of making a container body which consists in providing a metallic sheet having top and bottom edges and end edges, applying a non-metallic sheet to one side of said metallic sheet so as to leave a marginal part of the metallic sheet exposed along said top and bottom as well as the end edges thereof, flanging said top and bottom marginal parts of the metallic sheet over upon a portion of the non-metallic sheet to provide a partially finished flat blank, forming the end margins of said metallic sheet for future connection, rolling the partially finished flat blank in the plane of its end edges to impart a substantially tubular shape thereto open at both ends, and then operatively connecting the

previously formed end margins of the blank together.

3. The method of making a container body which consists in providing a metallic sheet having top and bottom edges and end edges, applying a non-metallic sheet to one side of said metallic sheet so as to leave a marginal part of the metallic sheet along one of the first mentioned edges thereof, flanging said marginal part of the metallic sheet over upon a portion of the non-metallic sheet, operating upon both end portions of the metallic sheet to form hook flanges overhanging portions of said non-metallic sheet to provide a partially finished blank, shaping the partly finished blank into approximate tubular form to bring said hook flanges into operative relation and applying a device to said hook flanges to secure said ends together.

4. The method of making a container body which consists in providing a metallic sheet having top and bottom edges and end edges, applying a non-metallic sheet to one side of said metallic sheet so as to leave a marginal part of the metallic sheet along the top and bottom edges thereof, flanging both of said marginal parts of the metallic sheet over upon adjacent portions of the non-metallic sheet, operating upon both end portions of the metallic sheet to form hook flanges overhanging portions of said non-metallic sheet to provide a partially finished blank, shaping the partly finished blank into approximate tubular form to bring said hook flanges into operative relation and applying a device to said hook flanges to secure said ends together.

5. The method of making a container body which consists in providing a metallic sheet having top and bottom edges and end edges, applying a non-metallic sheet to each side of the metallic sheet so as to leave a marginal part of the metallic sheet exposed along said edges thereof forming the end margins of said metallic sheet for future connection, flanging over said top and bottom marginal parts of the metallic sheet upon a portion of one of said non-metallic sheets to provide a partially finished blank, shaping said blank into open ended tubular form to bring the previously formed end margins of the metallic sheet together in operative relation and then securing said end margins together.

6. The method of making a container body which consists in providing a metallic sheet having top and bottom edges and end edges, applying a non-metallic sheet to each side of the metallic sheet so as to leave a marginal part of the metallic sheet exposed along said top and bottom edges thereof, flanging over said marginal parts of the metallic sheet upon adjacent portions of said one of said non-metallic sheet to form hook flanges thereon, rolling the partly finished blank to give it a substantially cylindrical form, bringing the hook flanges into operative relation and applying a device to said hook flanges to connect them together.

7. The method of making a container body which consists in providing a metallic sheet having top and bottom edges and end edges, applying a non-metallic sheet to one side of said metallic sheet so as to leave a marginal part of the metallic sheet exposed said edges thereof forming the end margins of said metallic sheet for future connection, flanging over said top and bottom marginal parts of the metallic sheet over upon a portion of the non-metallic sheet to provide a partially finished blank, shaping said blank into tubular form to bring the previously

formed end margins of the metallic sheet together in operative relation, securing said ends together to form a body and applying a closure to said last mentioned end of the body.

5 8. The method of making a container body which consists in providing a metallic sheet having top and bottom edges and end edges, applying a non-metallic sheet to each side of said metallic sheet so as to leave a marginal part of 10 the metallic sheet exposed along one of said first mentioned edges, flanging said marginal part over upon portions of both of said non-metallic sheets to provide a partially finished flat blank, bringing the ends of said blank into 15 operative relation and then securing them together.

9. As an article of manufacture, a blank for a container body comprising a metallic sheet member and a non-metallic sheet member secured to 20 one side thereof, the top and bottom portions of the metallic sheet member being flanged over

upon and in close engagement with associated portions of the non-metallic sheet, the ends of the metallic sheet being turned over toward adjacent portions of the non-metallic sheet to form hook flanges overhanging the same.

80

10. A container embodying therein a tubular body made from a blank comprising a metallic sheet member and non-metallic facing sheets, one on each side of and adhered throughout substantially its entire area to said metallic sheet member, end portions of said metallic sheet member being formed to provide flanges operatively connected together to hold said body in its tubular form, top and bottom portions of said metallic sheet member being turned over upon one of said facing sheets to provide a smooth edge flange extending around the entire top and bottom ends of the body and means for closing one end of said body.
